ETABLISSEMENTS SIEGEL & STOCKMAN REUNIS, OF SEINE, FRANCE.

FOOTLIGHT DEVICE.

Application filed June 11, 1927. Serial No. 198,141.

The invention relates to foot-light devices used for lighting store windows or for similar purposes, of the type using incandescent tube-shaped lamps of which each end is terminated by a preferably cylindrical metallic cap connected to the corresponding ends of the lamp filament so as to form the two poles thereof.

One object of the invention is to provide an easy way for inserting or removing the lamp. A further object of the invention is to provide the possibility of installing foot-lights of any desired length without use of any special strutting device, this being realized by the provision of a suitable number of supporting elements mounted in successive order according to the length of the lighting device which it is desired to establish.

0 The annexed drawing illustrates by way of example two embodiments of the device according to the invention. Figs. 1 to 4 show a preferred form; Figs. 1 and 2 show a support used for connecting the contiguous ends with like poles of two adjoining lamps, Fig. 1 being a front view, and Fig. 2 a section on line II-II (Fig. 3); Fig. 3 is a lateral view of the foot-light built up by a series of successively arranged tubes, the supporting elements being shown in section. Fig. 4 is a lateral view showing the foot-light on a reduced scale.

Figs. 5 and 6 illustrate another embodiment showing the device on a reduced scale in partial section, and lateral view respectively.

In Figs. 1 to 4, 1 designates the wall whereto it is proposed to fasten the foot-light. 2, 2' 2'' are tube-shaped lamps comprising each a luminous filament 3, the outer ends of which are electrically connected to two metallic caps 4 and 4^a respectively mounted upon the ends of the tube 2.

An insulating member 5 with a hollow 6 provided in its part turned towards the wall 1, is fastened to the latter by any suitable means, such as screws or the like. Inserted in this hollow 6 I provide a longitudinal metallic plate 7 which is fixed to the member 5 by a screw 9 in electrical contact with the plate 7, the latter comprising two junction sockets 8 protruding into the member 5. A transverse bore 10, drilled in member 5, provides for the passage of the feed wire 12, the end of which being held between

a screw 11 and the aforesaid screw 9 whereby an electrical contact is established between said wire, said plate and the sockets 8.

On the other hand, I can further provide another metallic sleeve 13 frictionally held upon each metallic cap 4 and 4^a respectively of every single lamp, this metallic sleeve 13 comprising a plug 14 adapted to be inserted and frictionally secured within one of said sockets 8; the sleeve 13 is enclosed within 65 an insulating cap 15 with slot 16 providing a passage-way for the plug 14.

By suitable spacing and fastening two similar contacts such as 5 and 5^a upon the wall 1, the electrical connection between the lamp and the feed wires 12 and 12^a will be established by inserting upon both lamp ends the caps 13-15 and 13^a-15^a respectively, plugs 14 and 14^a being inserted into the corresponding sockets 8 and 8^a respectively. It 75 is to be noted, both sockets 8 of each support being of like polarity, that the current will circulate in opposite directions in the two lamps of a pair of adjoining lamps.

By providing a suitable number of supports and lamps, a foot-light of any desired length can be mounted without difficulties in any place. Instead of straight lines, the foot-lights may also be mounted in broken lines, provided however that sufficient space be left between the two sockets 8 of a same support 5 to allow a lamp to be turned away at an angle from the adjoining one without interfering with their caps 15.

The junction parts 5, instead of being 80 separate, can be mounted in advance upon a same support, made, as shown in Figs. 5 and 6 by means of a U shaped metal bar. The construction shown in these figures is substantially the same as illustrated in the 85 preceding ones with the exception that the junction parts 5 are mounted within a rigid support 17 enclosing also the feed wires 12 and 12^a. The support used with this arrangement necessitates its previous assembly 100 in the work shop according to the required length of the respective foot-lights, and its subsequent shipping to the place where it is to be used, while the arrangement according to the preferred embodiment illustrated in 105 Figs. 1 to 4, allows the mounting in place of foot-lights of any shape or length by using a corresponding number of separate parts 5 and lamps 2.

It is well understood that the embodiments 110

as illustrated and described hereabove are not limiting and that the constructive forms may be widely varied without departing from the scope of the invention.

5 I claim—

1. A foot-light device of the type using tube-shaped lamps of which both ends are closed by metallic caps connected to the corresponding ends of the lighting filament, comprising a series of separate supports, two metallic interconnected junction sockets in each of said supports, a common terminal connecting both said junction sockets to the feed wire, a conductor sleeve provided upon each metallic end cap, and a plug on each sleeve disposed for cooperation with one of said junction sockets.
2. A foot-light device of the type using tube-shaped lamps of which both ends are closed by metallic caps connected to the corresponding ends of the lighting filament, comprising a series of separate supports, two metallic interconnected junction sockets in each of said supports, a common terminal connecting both said junction sockets to the feed wire, a conductor sleeve provided upon each metallic end cap, and a plug on each sleeve disposed for cooperation with one of said junction sockets, an insulating cap inserted upon said conductor sleeve, and a passage for the plug provided in said insulating cap.
3. A foot-light device of the type using tube-shaped lamps of which both ends are closed by metallic caps connected to the corresponding ends of the lighting filament, comprising a series of separate supports, two metallic interconnected junction sockets in each of said supports, a common terminal connecting both said junction sockets to the feed wire, a conductor sleeve provided upon

each metallic end cap, and a plug on each sleeve disposed for cooperation with one of said junction sockets, said separate supports being independent from each other.

4. A foot-light device of the type using tube-shaped lamps of which each end is provided with a metallic cap connected to the corresponding end of the lamp filament, comprising a number of supporting pieces made of insulating material and conformed to allow their fixation to any wall desired, a hollow provided upon the inner face of each of said supporting pieces, a metallic plate lodged within said hollow, a junction socket extending through said insulating piece provided upon each end of said metallic plate, a terminal upon said plate connecting the feed wire, at least one transverse hole provided in said insulating support for the passage of the feed wire and its connection to said terminal, a metallic conductor sleeve mounted upon each of said end caps, plugs on the sleeves disposed for cooperation with said junction sockets, and an insulating cap inserted upon each of said conductor sleeves.

5. A support made of insulating material, comprising at least two lugs, a hole provided in each of said lugs, a hollow upon the inner face of said support, a metallic plate lodged in said hollow, two connecting sockets provided upon said metallic plate extending through said insulating support, a terminal provided on said plate connecting the feed wire, and at least one transverse hole in said insulating piece leading to said terminal.

In testimony whereof, I have signed my name to this specification.

GEORGES WEIZSAEKER.
